UNITED STATES PATENT OFFICE.

EDWARD E. JENKINS, OF BALTIMORE, MARYLAND.

PEN AND PENCIL CLIP.

Application filed November 21, 1923. Serial No. 676,010.

To all whom it may concern:

Be it known that I, EDWARD E. JENKINS, a citizen of the United States, residing at Baltimore, State of Maryland, have invented or discovered certain new and useful Improvements in Pen and Pencil Clips, of which the following is a specification, reference being had therein to the accompanying drawing.

- 10 This invention relates to a clip for fountain pens or the like, and more particularly to that class of clips which are adapted to attach a pen or pencil to a vest pocket or other portion of the garment of the user.
- 15 The clips now most generally in use in connection with fountain pens, and which are adapted to attach the pen to the vest pocket of the user, are open to the objection that their efficiency is liable to be destroyed if 20 they are once bent outward too far, in that it is impracticable and nearly impossible to restore them to their original holding shapes. The present invention has for its object to avoid this objection by providing a 25 pen or pencil clip having so much elasticity that it will be practically impossible to destroy its efficiency by bending it outward from the pen casing or pencil to which it may be attached, as will hereinafter more 30 fully appear.

In the accompanying drawing Fig. 1 is a front view of a preferred form of the improved holder or clip, and Fig. 2 is a side view of the same attached to a fountain pen casing. Fig. 3 illustrates a slightly different form of the invention from that shown in Fig. 1, in operative position. Fig. 4 is a side view showing a modified form of the invention attached to a fountain pen, and 40 Fig. 5 is a top view of the form of the invention shown in Fig. 4.

Referring to the drawing, 12 denotes the body of the spring clip and which body consists of a flat volute coil of spring wire 12, 45 preferably of elongated or oval form as shown more clearly in Fig. 1, but which may be of circular volute or spiral form as shown in Fig. 3.

From the center of the coil 12, and preferably integral therewith, extends an attaching member which has a short shank portion 13 from which extends upward a thin flattened portion 14. This form of the inven-

tion is adapted for attachment to a fountain pen cap as shown in Fig. 2, the attaching portion 14 extending between a sleeve 15, within the cap 16, and the said cap, this mode of attachment being the same as that now in use with many fountain pens. Also integral with the coil 12 is a spring arm or member 17 adapted to grip against a pocket portion 18, or the like, of the garment of the user, as shown in Fig. 3; the lower end of said spring arm or member 17 being preferably turned outward or rounded to facilitate the attachment of the pen to the garment of the user.

Instead of being provided with the holding member 14 a spring-gripping member, as 19, may be soldered or riveted directly to the 70 spring body part 12, said gripping member being adapted to engage the outside of a fountain pen holder, as 20, as shown in Fig. 4.

From the foregoing it will be understood 75 that the flat volute coil 12 which forms the body of the clip will have such great elasticity that it will be practically impossible to injure or destroy the gripping capacity 80 of the clip by bending the holding arm or member 17 outward, the very considerable length of spring wire in the flat coil affording such great elasticity that the clip will strongly grip the garment to which it may be attached, so as to securely hold the pen or 85 pencil provided with the improved clip in place, while affording such a construction that it will be practically impossible to destroy the gripping capacity of the clip by pulling the gripping member 17 outward. 90

Having thus described my invention, I claim and desire to secure by Letters Patent:

1. A pen or pencil clip comprising a flat volute coil or spring wire having an integral extension affording a gripping member, said 95 wire coil being provided with means for attaching the same to a pen or pencil.

2. A pen or pencil clip comprising a flat, elongated or oval volute coil of spring wire having an integral extension affording a 100 gripping member, said wire coil being provided with means for attaching the same to a pen or pencil.

3. A pen or pencil clip comprising a flat volute coil of spring wire having an integral 105 extension affording a gripping member, said

- wire coil having, extending from its central portion, an integral flattened portion adapted to be inserted in the cap of a fountain pen between such cap and a sleeve therein.
- 5 4. A pen or pencil clip comprising a flat, elongated or oval volute coil of spring wire having an integral extension affording a

gripping member, said wire coil having, extending from its central portion, an integral flattened portion adapted to be inserted in the cap of a fountain pen between such cap and a sleeve therein.

In testimony whereof I affix my signature.

EDWARD E. JENKINS.
